ATTORNEY.

UNITED STATES PATENT OFFICE.

GEORGE D. CLARK, OF PLAINVILLE, CONNECTICUT.

DESIGN FOR A CASTER-SOCKET.

SPECIFICATION forming part of Design No. 32,291, dated February 27, 1900.

Application filed December 30, 1899. Serial No. 742,160. Term of patent 14 years.

To all whom it may concern:

Be it known that I, GEORGE D. CLARK, a citizen of the United States, residing at Plainville, county of Hartford, State of Connecticut, have invented and produced a certain new and original Design for a Caster-Socket, of which the following is a full, clear, and exact description.

My invention relates to a new and original design for a caster-socket.

In the accompanying drawings, Figure 1 is a side elevation. Fig. 2 is a plan view.

The leading features of my design are best shown in Fig. 1, in which A is a cylindrical lower portion abruptly contracted toward its upper end and surmounted by an upper cylindrical portion B, which is of slightly-smaller diameter.

D is a flange which projects from the lower portion A. 20

The upper portion B has a rounded appearance, as at E.

F are longitudinal openings in the upper portion B.

G is a central opening extending longitudinally through the socket. 25

What I claim is—

The design for a caster-socket substantially as herein shown and described.

Signed at Plainville, Connecticut, this 6th day of December, 1899. 30

GEORGE D. CLARK.
